UNITED STATES PATENT OFFICE

ELMER W. SHIVELY, OF CARLETON, NEBRASKA

FENCE WIRE FASTENER

Application filed September 8, 1931, Serial No. 561,805. Renewed June 13, 1932.

This invention relates to an improved fence wire fastener which is especially but not necessarily adapted for use and association with a metal fence post of a T-shaped form having vertically spaced lugs formed on its wire contacting sides.

I am aware of the fact that the art to which the invention relates is appreciably well developed and comprehends many distinguishable types of attaining and fastening devices designed to facilitate expeditious connection and maintenance of fence wires, on an associated post. Most of these fasteners so far as I am aware fail to accomplish the desired result of expeditious application and removal and subsequent secure maintenance of the fence wire.

My familiarity with fastening devices in the trade and prior art has enabled me to discover the need for a more satisfactory fastener. This I have done by providing a device of the type illustrated in the drawing, and the specific formation and features of this device will become more readily apparent as the description proceeds.

In the drawing:

Figure 1 is a front view of a fragmentary portion of a post showing fence wires and a pair of fasteners for said wires. Figure 2 is a horizontal sectional view through the post showing the method of application and secure maintenance of the fastener.

In the drawing the fence post is distinguished by the numeral 3 and comprises a plate portion 4 and a rib or flange 5. This is an ordinary type of T-shaped post now used for mounting fence wires. The fence wires are denoted by the numeral 6 while the numerals 7 are employed to designate common types of longitudinally spaced vertically disposed lugs or stops. The improvement is predicated upon the selection and formation of parts constituting the fastener per se and this fastener is made up of two companion parts distinguished by the numerals 8 and 9 respectively. The parts 8 cooperate with a plate 4 while the part 9 is engageable with the edge portion of the flange 5 as depicted in Figure 2. Both parts are formed

from a single length of wire, the wire constituting the part 8 is bent to provide a wire binding portion 10 having a hook 11 at one end preferably engageable with plate 4.

The intermediate portion of this part 10 is bent to intersect and clamp the fence wire in place. The free end portion of the wire comprises a terminal 12 having an eye 13 interconnected with a complementary eye 14 on the part 9. Incidentally as a matter of further distinction part 8 may be designated as a hooked clip while the part 9 may be designated as a latch-like keeper. Said part is formed from a single length of wire bent between its ends to form a V-shaped grip 15 of appropriate yieldable properties one arm being formed with the eye 14 and the other arm with a similar eye 16 so that the eye 16 forms a finger grip or means for grasping the part 9 with a pair of pliers for attaching and removing it.

In practice the hook 11 is engaged over the plate 4 and the part 10 is placed in a position to intersect the wire 6. This allows the terminal portion 12 to extend rearwardly toward the flange 5 and inasmuch as this part 12 carries the keeper 9, said keeper is allowed to be releasably snapped over the flange to take the position depicted in Figure 2. In this position the fence wire is securely maintained on the post. It is permissible however to take up a pair of pliers and to grasp the eye 16 and to actuate the part 9 in such a manner as to releasably snap from engagement with the flange 5.

The novelty is predicated upon the two part structure one part releasably engageable with the plate 4, the other part engageable with the flange 5, said parts being hingedly connected together and so fashioned as to properly embrace the post and wire to securely maintain the fence wire in place.

It is thought that the description taken in connection with the drawing will enable a clear understanding of the invention to be had. Therefore, a more lengthy description is thought unnecessary.

While the preferred embodiment of the invention has been shown and described, it is to be understood that minor changes coming

within the field of the invention claimed may be resorted to if desired.

Having thus described my invention, what I claim as new is:

- 5 1. In a structure of the class described, in combination a T-shaped fence post, a fence wire, and a fastener for securing said fence wire to the post, said fastener comprising a pair of complemental hingedly connected sections, one section being releasably connected with the plate portion of the post and intersecting and securing wire to said post and the other section being yieldably and releasably engageable with the flange portion of the post.
- 10 15. 2. As a new product of manufacture, a fence wire fastener comprising a pair of companion parts, one part being adapted to embrace the plate portion of a post in a manner to intersect the adjacent portion of the fence wire, said part being formed with a post engaging hook, the remaining part being hingedly connected to the first named part and shaped as to yieldably and releasably engage the flange of said fence post.
- 20 25. 3. As a new product of manufacture, a fence wire fastener comprising a primary wire anchoring section formed from a single length of wire bent at one end to provide a retaining hook having its opposite end bent and formed with a terminal eye adapted to project rearwardly in the direction of the flange of the post, and a V-shaped part releasably engageable with said flange and including an eye hingedly interlocked with said first named eye.
- 30 35. 4. A fence wire fastener comprising a substantially V-shaped wire member adapted to straddle the flange of a T-shaped fence post, the opposite arm of said member being formed with eyes, one eye adapted to accommodate a tool, and a second post engaging member comprising a single length of wire bent at one end to form a hook having its opposite end formed with an inclined extension having an eye hingedly and interlockedly connected with the adjacent eye.

In testimony whereof I affix my signature.
ELMER W. SHIVELY.
